UNITED STATES PATENT OFFICE.

WESTON A. PRICE, OF CLEVELAND, OHIO, ASSIGNOR TO THE ELECTRIC AND DENTAL SPECIALTY COMPANY, OF CLEVELAND, OHIO, A CORPORATION OF OHIO.

DESIGN FOR A RHEOSTAT OR CONTROLLER COVER.

SPECIFICATION forming part of Design No. 36,399, dated June 30, 1903.

Application filed February 24, 1903. Serial No. 144,928. Term of patent 14 years.

To all whom it may concern:

Be it known that I, WESTON A. PRICE, a citizen of the United States, and a resident of Cleveland, county of Cuyahoga, and State of Ohio, have invented a new, original, and ornamental Design for Rheostat or Controller Covers, of which the following is a specification, reference being had to the accompanying drawings, forming part thereof.

Figure I is a plan view of a rheostat or controller cover, showing my new design; and Fig. II is a side view thereof.

Having described my invention, what I claim as new, and desire to secure by Design Letters Patent, is—

The ornamental design for a rheostat or controller cover, as shown.

In testimony whereof I have signed my name to this specification in the presence of two subscribing witnesses.

WESTON A. PRICE.
